CLAIM

The ornamental design for a telescoping squeegee, as shown and described.

DESCRIPTION

FIG. 1 is a top, rear perspective view for a telescoping squeegee, showing our new design;

FIG. 2 is a front view thereof;

FIG. 3 is a rear view thereof;

FIG. 4 is a left side view thereof;

FIG. 5 is a top view thereof; and,

FIG. 6 is a bottom view thereof.

The broken lines depict portions of the telescoping squeegee that form no part of the claimed design.
